UNITED STATES PATENT OFFICE.

STEPHEN O'BRIEN, OF NEW YORK, N. Y.

SHEET-METAL-EDGING MACHINE.

Application filed November 7, 1924. Serial No. 748,333.

This invention relates to a machine for edging sheet material, and relates more particularly to a machine for flanging the edges of sheet metal.

5 A prime object of the present invention comprehends the provision of a sheet metal edging machine in which the edge forming mechanism or tools are designed, constructed and inter-related to operate upon sheet metal fed thereto to produce flanged edges of uniform characteristics. In edging machines of known designs and types, it has been found difficult to produce flanged edges of uniform or constant width and angularity, such machines requiring the skillful handling and feeding of the metal to the forming tools by trained workers or operatives where consistent results in producing a uniform product are desired. To overcome the difficulties inherent in these machines of prior designs, and to produce an edge forming machine in which the sheet metal is automatically operated upon by the forming tools for producing flanged edges of consistent characteristics such as uniform width and angularity, is a prime desideratum of my present invention.

Further principal objects of my present invention include the provision of an edging machine in which the parts are constructed and relatively arranged so that the strains and stresses produced by the operation of the forming mechanism on the sheet metal are efficiently supported and counteracted, yielding a well balanced structure and one in which wear and tear is minimized; the further provision of a sheet metal edging machine designed to accommodate sheet metal of different thicknesses, the parts being adjustable by the operative in a simple manner to suit the stock employed; and the still further provision of an edging machine embodying relatively simple mechanism capable of facile operation and easy adjustment and repair, the whole providing a comparatively inexpensive assembly capable of being used and manipulated by unskilled help.

To the accomplishment of the foregoing and such other objects as will hereinafter

appear, my invention consists in the elements and their relation one to the other, as hereinafter particularly described and sought to be defined in the claims; reference being had to the accompanying drawings which show the preferred embodiment of my invention, and in which:

Fig. 1 is a perspective view of the edging machine of my present invention,

Fig. 2 is a side elevational view thereof with parts shown in cross-section,

Fig. 3 is a plan view thereof taken in cross-section on the line 3—3, Fig. 2, and

Fig. 4 is a diagrammatic and fragmentary view of the forming tools shown on an enlarged scale.

Referring now more in detail to the drawings, in which I show a preferred embodiment of my invention, the edging machine comprises a supporting structure or frame ⁷⁰ *f* which may be a suitable casting of rectangular formation having a bottom wall 10, a top wall 11 and the front and rear walls 12 and 13, the said frame being provided with an integral standard or stud post 14 for ⁷⁵ supporting the frame in operative position. The frame *f* supports the operative parts of the edging machine, including a main drive shaft 15 and a second shaft 16 geared to the main drive shaft 15 by means of the ⁸⁰ meshing pinions 17 and 18 fixed respectively to the shafts 15 and 16, both shafts being journaled, as will be described more in detail hereinafter, in the front and rear walls 12 and 13 of the frame *f*. The shaft ⁸⁵ 15 has an extension 15' which is designed to be connected to any suitable source of power for driving the same, and when operated will impart rotation to the shaft 16 for positively operating in mating relation the edge ⁹⁰ forming tools *e* and *e'* which are secured to the ends of the shafts 15 and 16, as clearly shown in the drawings.

As heretofore stated, a prime desideratum of my present invention comprehends the ⁹⁵ provision of a sheet metal edging machine in which the edge forming mechanism or tools are designed, constructed and inter-related to operate upon sheet metal fed thereto to produce automatically flanged ¹⁰⁰

edges of uniform width and angularity. To these ends the edge forming mechanism or tools e and e' embody structure for operating upon the sheet metal fed thereto to assure the uniform inturning or flanging of the metal edges. In the preferred embodiment of the invention, as exemplified in the drawings, the edge forming tools e and e' comprise male and female edging rolls embodying means for automatically producing flanged edges of predetermined widths.

More specifically, the female edging roll e is provided with an annular channel 19 defined by an edge forming face 20, and a curved or concave edge guiding face 21 the radius of curvature of which is substantially equal to the width of the edge to be formed, and as diagrammatically shown in Fig. 4 of the drawings, the curved or arcuate-shaped face 21 has a radius of curvature r the center of which is at the angle of the forming faces 20 and 22 of the female roll. The male edging roll e' is provided with an annular flange shaped member 23 which mates with the annular channel 19 of the female roll for operating upon the edge of a sheet metal blank b to flange the same, as is clearly shown in Figs. 1 and 2 of the drawings. With this construction it will be apparent that the edging rolls will operate to force the edge of the metal blank into the annular channel of the female roll, and that the guide face 21 of the forming channel will guide the edge of the metal fed thereto, as is shown in Fig. 2 of the drawings, so as to prevent any increase in the width of the metal that is being inturned or flanged, the construction operating to assure the production of flanges of predetermined and uniform widths.

In the operation of the machine, as will be evident for example from a consideration of Fig. 2 of the drawings, the cooperation of the edge forming faces of the edging rolls e and e' produces opposed axial thrusts and stresses on the shafts 15 and 16, and for the purpose of suitably supporting and efficiently counteracting these stresses, I provide bearing means for the shafts 15 and 16 constructed to act axially in opposition, suitably supporting the stresses not only, but producing efficient mating relation between the edge forming rolls e and e' . Accordingly, the shaft 15 is provided with a ball bearing support generally designated as 24 having a stator section 24' fixed to the rear wall 13 of the frame f and having a rotor section 24" fixed to the shaft 15, the ball bearing sections cooperating to support the axial thrust which is produced on the edging roll e . The shaft 16 is in turn provided with a ball bearing structure 25 designed to support the axial thrusts on the shaft 16 which are produced on the edging roll e' , these thrusts being in a direction opposed to those produced

on the shaft 15. The ball bearing structure 25 also comprises a stator section 25' which is movably secured to the frame f in a manner to be described presently, and a rotor section 25" which is fixed to the shaft 16. 70

To adapt the apparatus for different dimensions of sheet metal stock, and to adjust the machine for the operation desired, the male edging roll e' and its operating shaft are mounted so as to be capable of adjustment by the operative. To these ends, I provide means which may be manually manipulated for moving the shaft 16 axially and laterally relatively to the shaft 15, the axial motion being produced by manually manipulated means generally designed as m and the lateral adjustment being effected by means generally designated as m' .

The adjusting means m in the preferred construction comprises a yoke member 26 having arms 27 and 28 secured to frame extensions 29 and 30, the said yoke member supporting the ball bearing 25 by means of the trunnions 31. The yoke member 26 is movable to and from the frame wall 13 by means of the hand lever 32 which is threadedly received by the shank 33 of a bolt 34 pivotally movable as at 35 on the top wall 11 of the frame, the said lever 32 engaging the rear wall of the yoke member 26 for moving the same against the action of a spring 36 which encircles the bolt shank 33. 80

The adjusting means m' for securing the lateral motion of the shaft 16 may comprise a crank arm 37 threadedly received by the frame wall 11, the said crank arm having a shank 38 which engages a block 39 in which the shaft 16 is journaled, the said block being movable in the opening 40 provided in the front frame wall 12. Cooperating with the crank arm 37 there is provided a spring 41 seated against the block 39 so as to be active in opposition to the crank arm 37 and cooperating therewith to position the shaft 16. 95

With this construction it will be apparent that the machine may be adjusted to accommodate stock of different thicknesses, the manually manipulated means m and m' being coordinately operated to produce the desired results. In the preferred operation of the machine, the edging of the sheet metal is accomplished in two separate steps, the first step producing a substantially 45° bend in the metal and the second step producing a 90° bend, as shown for example in Figs. 1 and 2 of the drawings. The same machine may be employed for both operations or steps by the adjustment of the manually manipulable mechanism m and m' described. 115

The operation and use of my improved sheet metal edging machine and the advantages thereof will in the main be fully apparent from the above detailed description thereof. It will be further apparent that I 120

have provided a machine embodying relatively simple mechanism for automatically operating upon sheet metal edges to produce flanges of uniform and consistent characteristics, the machine being capable of being used by unskilled operatives. It will be

further evident that the parts of the machine are adapted for easy adjustment to accommodate or suit different stock and to produce both operating steps, the parts of the machine being relatively coordinated to minimize wear and tear and to permit facile and rapid operation.

While I have shown my device in the preferred form, it will be obvious that many changes and modifications may be made in the structure disclosed without departing from the spirit of the invention, defined in the following claims.

20 I claim:

1. A machine for edging sheet material comprising male and female edging rolls, the female edging roll having an annular channel formed therein and defined by a straight edge forming face and a curved edge guiding face the radius of curvature of which is substantially equal to the width of the edge to be formed.

2. A machine for edging sheet material comprising male and female edging rolls, the female edging roll having an annular channel formed therein and defined by an edge forming face and a curved edge guiding face the radius of curvature of which is substantially equal to the width of the edge to be formed, the said male edging roll including an annular member mating with the annular channel of the female edging roll.

3. A machine for edging sheet material comprising male and female edging rolls, a pair of shafts carrying the edging rolls geared to be driven together, the female edging roll having an annular channel formed therein and defined by an edge forming face and a curved edge guiding face the radius of curvature of which is substantially equal to the width of the edge to be formed, the said male edging roll including an annular member mating with the annular channel of the female edging roll.

4. A machine for edging sheet material comprising a shaft, a female forming roll thereon, a second shaft, a male forming roll on the second shaft mating with the female forming roll, the said female forming roll having an annular channel defined by an edge forming face and a curved edge guiding face the radius of curvature of which is substantially equal to the width of the edge to be formed, the male forming roll having a face cooperating with the female roll active in producing opposed axial thrusts on the shafts, a ball bearing for the first men-

tioned shaft supporting the same against axial thrusts in one direction and a ball bearing for the second shaft supporting the latter against axial thrusts in the opposite direction.

5. A machine for edging sheet metal comprising a shaft, an edging tool thereon, a second shaft, an edging tool on the second shaft mating with the edging tool on the first shaft, means for supporting the second shaft to move the same axially and laterally relatively to the first mentioned shaft, and means manually manipulable during the operation of the machine for effecting the axial and lateral adjustment 70 of said second shaft.

6. A machine for edging sheet material comprising a shaft, a female edging roll thereon, a second shaft, a male edging roll on the second shaft, the said female edging 85 roll having an annular channel formed therein and defined by an edge forming face and a curved edge guiding face of uniform curvature, and means for adjusting the second shaft axially and laterally relatively 90 to the first shaft.

7. A machine for edging sheet material comprising a shaft, an edging roll thereon, a second shaft, an edging roll on the second shaft mating with the edging roll on the 95 first shaft, manually manipulable means for moving the second shaft laterally of the first shaft and manually manipulable means for moving the second shaft axially relatively to the first shaft, both of said means 100 being simultaneously operative during the operation of the machine for adjusting one edging roll relatively to the other.

8. A machine for edging sheet material comprising a frame, a shaft journaled in 105 the frame, an edging tool fixed to said shaft, a second shaft geared to the first mentioned shaft, an edging tool on the second shaft, and adjustable bearing means for the second shaft including a yoke member supported by the frame and manually manipulable means for moving the yoke member 110 during the operation of the machine.

9. A machine for edging sheet material comprising a shaft, a forming roll thereon, 115 a second shaft, a forming roll on the second shaft mating with the forming roll on the first shaft, the forming rolls including edge forming faces cooperating with each other and active in producing opposed axial 120 thrusts on said shafts, and adjustable bearing means for the second shaft including an adjustable block movable in the frame of said machine against the axial thrusts on the shaft, and a yoke member supported by 125 and adjustable relatively to said machine frame.

10. A machine for edging sheet material comprising a frame, a shaft journaled in 130 the frame, an edging tool fixed to said shaft,

4
a second shaft geared to the first mentioned shaft, an edging tool on the second shaft, and adjustable bearing means for the second shaft including a block movable in said frame, manually manipulable means for adjusting the block, a yoke member supported by and movable relatively to the frame, a

ball bearing supported in the yoke member, and manually manipulable means for moving the yoke member.

10

Signed at New York city, in the county of New York and State of New York, this 3rd day of November, A. D. 1924.
